(57) **CLAIM**

What is claimed is the ornamental design for a flotation vest, as shown and described.

DESCRIPTION

FIG. 1 is a front perspective view of a flotation vest, showing the new design in a collapsed configuration;

FIG. 2 is a top plan view of FIG. 1;

FIG. 3 is a bottom plan view of FIG. 1;

FIG. 4 is a front elevational view of FIG. 1;

FIG. 5 is a rear elevational view of FIG. 1;

FIG. 6 is a right-side elevational view of FIG. 1;

FIG. 7 is a left-side elevational view of FIG. 1;

FIG. 8 is a left-side elevational view thereof, illustrated in an inflated configuration;

FIG. 9 is a rear elevational view of FIG. 8; and,

FIG. 10 is a rear perspective view of FIG. 8.

The broken lines in the figures are for environmental purposes only and form no part of the claimed design.
